CLAIM

The ornamental design for a coffee pot or similar article, substantially as shown and described.

DESCRIPTION

FIG. 1 is a side elevational view of a coffee pot or similar article showing my new design, the reverse side being a mirror image thereof;

FIG. 2 is a sectional view thereof, taken along the lines 2—2 of FIG. 3;

FIG. 3 is a top plan view thereof;

FIG. 4 is a left side elevational view thereof;

FIG. 5 is a right side elevational view thereof;

FIG. 6 is a bottom plan view thereof.

FIG. 1

FIG. 2

FIG. 3

FIG. 4

FIG. 5

FIG. 6
